UNITED STATES PATENT OFFICE.

SAMUEL GOLDBERG, OF NEW YORK, N. Y., ASSIGNOR TO GOLDBERG & SQUIRE, INCORPORATED, OF NEW YORK, N. Y., A CORPORATION OF NEW YORK.

NECKTIE.

Application filed November 8, 1927. Serial No. 231,823.

The four-in-hand necktie of the present invention is of the character in which the normally folded back edges of the tie ends are only removably secured together, and may 5 be fully opened and laid flat to facilitate pressing and cleaning when the tie becomes rumpled and soiled.

A primary object of the invention is to provide, in a tie of this character, novel means 10 for releasably holding the normally folded back edges of the tie ends in proper position, yet means capable of ready movement to release said folded back portions and permit full opening and convenient pressing of the 15 tie ends.

Another object of the present invention is to provide releasable securing means of this character which will not become unfastened when the usual pulling and twisting strains 20 are imposed upon the tie ends as an incident of knotting the tie. The novel securing means which I utilize resists undue distortion of the tie as the knot is being formed and tightened, and relieves the tie fabric of considerable strain.

Still another object of the invention is to provide securing means which cannot become lost or damaged while the tie is being pressed.

A more specific object of the invention is 30 to provide securing means in the nature of a flexible device laced through aligned openings in the folded back and overlapped tie edges, the openings being so arranged and the flexible device being so laced through them, 35 that accidental opening of the folded back flaps or casual slippage or displacement of the flexible device is substantially prevented. In other words, the lacing is in effect self locking against accidental loosening.

Another object is to provide a securing lacing of this character which is almost entirely concealed from view.

Further objects of the invention are to provide a tie of simple, practical construction, 45 which may be readily pressed and cleaned, which will be neat and attractive in appearance, and rugged and durable in use.

With the above noted and other objects in view, the invention consists in certain novel 50 features of construction and combinations and arrangements of parts, as will be more fully hereinafter set forth and pointed out

in the claims. The invention may be more fully understood from the following description in connection with the accompanying 55 drawings, wherein:

Fig. 1 is a perspective view, the smaller end of the tie being slightly unfolded to expose the securing means, and the securing means being shown in process of removal from the 60 larger end of the tie.

Fig. 2 is a transverse sectional view on the line 2—2 of Fig. 1.

Fig. 3 is an enlarged vertical sectional detail on the line 3—3 of Fig. 1.

The body or outer facing of the tie is numbered 10 and the similarly shaped lining or inner facing designated at 11. The body and lining are secured together along their side edges and across the ends of the tie by lines 70 of stitching 12. The lining may either be a unitary member, or may comprise two pieces secured to the two ends of the body and terminating approximately at the narrow collar-encircling intermediate portion of the tie. 75 In the latter instance, the narrow ends of the lining pieces are anchored by the lines of cross stitching 13.

Such lines of stitching as well as the additional stitching 14 is to permanently secure 80 the narrow, folded, intermediate collar encircling portion of the tie against opening.

The sides of the flaring tie ends are folded back in the usual manner with their edges overlapping throughout a portion of their 85 length. These overlapped edges are provided with registering slits, slots or eyes 15 through which my improved flexible securing and reinforcing device 16 is laced.

Member 16 comprises a length of fairly substantial tape or equivalent material. Its free extremities which are preferably tipped as at 17 to facilitate threading them through openings 15, are concealed by the folded back portion of the tie ends. The intermediate portion of the tape 16 is covered and concealed by the collar encircling portion of the tie and anchored by the stitching 13. If desired the tape instead of extending through the collar encircling section of the tie, might be formed 95 as two pieces each anchored at one end to such section.

If the aligned pairs of openings 15 were spaced equal distances apart, approximately

half of the tape would be exposed and the tape might be very readily accidentally displaced, or drawn out, thus forming undesirable hanging loops at the exterior of the tie. 5 To prevent this I arrange the sets of openings in closely adjacent pairs with relatively long spaces between the pairs. The tape is exposed only throughout the short space between two closely adjacent openings and concealed 10 for most of its length. The double bend formed in a short length of tape by making the emerging tape end almost immediately re-entrant produces in effect a locking action. The possibility of accidental displacement of 15 the tape is avoided and a firm contact between the overlapped flaps is had wherever the two sets of adjacent openings occur.

Suitable interlining or stiffener material (not shown) may be interposed if desired, 20 between the tie body 10 and lining 11, but preferably the body and lining are of fairly heavy silk or equivalent material which renders such interlining unnecessary.

When it is desired to unfold the tie ends to 25 press the tie, the tape is unlaced and the tie pressed flat. The tape is then replaced through the slots 15 and the pressing operation accurately completed.

When knotting the tie, the wearer of necessity pulls on both ends thereof. The tape 30 at this time acts as a reinforcement, relieving the tie body from much of the pulling strain. Thus, the tape is far superior to tacking which is readily broken when knotting the tie, and to separable fasteners which 35 may be crushed or broken by the pressure of an iron.

Obviously various changes and alterations 40 might be made in the construction of the tie without departing from the spirit and scope of the appended claims.

I claim:

1. A four-in-hand necktie including a relatively narrow collar encircling intermediate portion, and a pair of flaring tying ends, the side edges of one of said tying ends being folded back upon the intermediate portion thereof and overlapped, said overlapping edge portions having a longitudinal 45 series of aligned openings therein, and a flexible securing device removably laced through the openings.

2. A four-in-hand necktie including a permanently folded over and stitched down collar encircling intermediate portion, and a pair of flaring tying ends, the side edges of one of said tying ends being folded back upon the intermediate portion thereof and overlapped, said overlapping edge portions 50 having aligned openings therein, and a flexible securing device removably laced through the openings, said securing device comprising a flat tape, the free end of which is laced through the openings.

3. A four-in-hand necktie including a rel-

atively narrow collar encircling intermediate portion, and a pair of flaring tying ends, the side edges of one of said tying ends being folded back upon the intermediate portion thereof and overlapped, said overlapping edge portions having openings therein, and a flexible securing device removably laced through the openings, said securing device comprising a flat tape, the free end of which is laced through the openings, said tape 75 being anchored to the collar encircling portion of the tie.

4. A four-in-hand necktie including a relatively narrow collar encircling intermediate portion, and a pair of flaring tying ends, the 80 side edges of one of said tying ends being folded back upon the intermediate portion thereof, a removable flexible connecting device extending longitudinally of the tie laced through and connecting said folded back 85 portions.

5. A four-in-hand necktie including a collar encircling intermediate portion, and a pair of flaring tying ends, the side edges of one of said tying ends being folded back 90 upon the intermediate portion thereof, a flexible device anchored to the neck-encircling portion of the tie and including a free end retaining the folded back edges in folded position.

6. A device as set forth in claim 1, wherein both ends of the tie are similarly constructed, and the flexible device is anchored at its intermediate portion, and includes a pair of free ends laced through the respective tie ends. 95

7. A four-in-hand necktie including a relatively narrow collar encircling intermediate portion, and a pair of flaring tying ends, the side edges of one of said tying ends being folded back upon the intermediate portion 100 thereof and overlapped, said overlapping edge portions having aligned openings therein, and a flexible securing device removably laced through the openings, the aligned openings being arranged in closely adjacent pairs 105 with relatively long unapertured sections of tie between them.

8. A four-in-hand necktie including a relatively narrow collar encircling intermediate portion, and a pair of flaring tying ends, the side edges of one of said tying ends being folded back upon the intermediate portion thereof and overlapped, said overlapping edge portions having aligned openings therein, and a flexible securing device removably 115 laced through the openings, the aligned openings being arranged in closely adjacent pairs with relatively long unapertured sections of the tie between them, the flexible device being disposed on the outside of the tie only in 120 the short spaces between the openings of an adjacent pair.

9. A four-in-hand necktie including a relatively narrow collar encircling intermediate portion, and a pair of flaring tying ends, the 130

side edges of one of said tying ends being folded back upon the intermediate portion thereof and overlapped, said overlapping edge portions having aligned openings therein, and a flexible securing device removably laced through the openings, the openings being so arranged that only a few relatively

short sections of tape are exposed at the exterior of the tie with relatively long sections of tie between them.

10

Signed at New York, in the county of New York and State of New York this (7th) seventh day of November A. D. 1927.

SAMUEL GOLDBERG.
